UNITED STATES PATENT OFFICE

GUSTAF ALEXANDER, OF CHICAGO, ILLINOIS

WATER CRAFT

Application filed August 14, 1931. Serial No. 557,124.

This invention relates to watercraft, and has for its principal object to improve generally upon power driven vessels for various special uses and of various capacities, tonnage and displacement. Special objects and advantages to be attained are to secure high efficiency in propulsion and speed from a minimum of power, to provide for simplicity and ease of effective steering control, to produce a balanced stabilizing structure for a steady and smooth riding effect, and to attain certain other advantages which will more fully appear in the following description.

The invention consists in the novel general structural arrangement and in the particular parts and combinations and arrangements of parts hereinafter described and pointed out with particularity in the appended claims.

In the accompanying drawing, forming a part of this specification and illustrating an adaptation of the invention,

Fig. 1 is a top plan view;

Fig. 2 is a longitudinal section on the line 2—2 of Fig. 1;

Fig. 3 is a transverse section on the line 3—3 of Figs. 1 and 2;

Fig. 4 is a cross-section, on an enlarged scale, through the keel tube or tunnel portion of the boat in the region of the propeller, the line of section being approximately the same as that on which Fig. 3 is taken;

Fig. 5 is a fragmentary view on an enlarged scale, partly in longitudinal section and partly in side elevation, showing the driving gear;

Fig. 6 is a fragmentary plan view to illustrate the rudder locking device; and

Fig. 7 is a partial section and side elevation further illustrating details of the rudder locking device.

Referring now to the drawing, the numeral 10 designates generally the hull of the vessel, which may obviously be constructed throughout of sheet metal or partially of wood or other suitable material, as may be desired. As

shown more clearly in Fig. 3 of the drawing, the main body portion of the hull may be provided with air chambers 11 at its sides and bottom. At each end of the structure shown the hull is tapered upwardly at a consider-

able angle from the under side, as at 12, and

slightly downward at the top where it is covered by a deck or hood portion 13, said end portions also tapering on opposite sides convergently, as at 14, the extreme end portions terminating in a comparatively sharp horizontal edge or prow 15. Preferably, the deck or hood portion 13 is hingedly mounted, as at 16, at the prow, whereby to be swung over to a forwardly projected position so as to serve as a landing bridge between the boat and a dock or shore landing place, as indicated by dotted lines in Fig. 2 of the drawing.

Extending longitudinally and medially of the bottom of the hull is a keel tube or tunnel portion 17, said tube or tunnel being open at its opposite ends. Located preferably midway between the ends of the tube or tunnel portion 17 is a propeller 18 of suitable construction and having any desirable number of blades, said propeller, for the purposes particularly intended, being rotatable about a longitudinal axis and having its blades set so as to be equally effective when rotated in either direction. When operated the propeller draws the water in at the forward end of the tube or tunnel 17, according to the direction of travel of the vessel, and ejects it forcibly in a column from the rear end thereof.

Any suitable driving means may be employed for the propeller. As shown, the propeller shaft 19 has a bevel gear 20 fixed thereon and engaging a similar gear 21 on the lower end of a vertical countershaft 22, said countershaft having another like gear 23 fixed on its upper end portion. Cooperatively engaging the gear 23 is a pair of opposed gears 24 and 25 which are respectively mounted loosely on the driving shaft 26 of a motor 27 of any desirable kind. As shown, the gear 24 is held in working relation to the gear 23 by an annular abutment or collar 28 which is pinned or otherwise fixedly secured on the shaft. Likewise, the gear 25 is held in working relation to the gear 23 by an abutment or boss 29 which, as shown, is a part of the end bearing for said driving shaft 26. By this arrangement the two gears 24 and 25 are normally idle while the driving shaft is rotating, and to alternately couple said gears 24 and 25.

25 to the driving shaft so as to impart motion to said gears 24 and 25 respectively and thereby drive the gear 23 in opposite directions, at will, the driving shaft 26 is provided with a longitudinally shiftable clutch device which 5 may be normally placed in a neutral position between the two gears 24 and 25. As shown more clearly in Fig. 5 of the drawing, the clutch device comprises an annular member 30 which is obviously provided with a key or spline working in a longitudinal groove 31 formed in the shaft. By this arrangement the clutch member, of course, rotates with the shaft 26 but is freely shiftable longitudinally thereof, the opposite end faces of said member 30 having annular series of teeth 32 formed thereon for engagement with counterpart teeth 33 formed on hub extensions 34 and 35, respectively, of the two opposed gears 24 and 25. The clutch member 30 is provided with an annular circumferential groove 36 in which is rotatably fitted a collar or shifter ring 37 having diametrically opposed arms or trunnions 38 to which the bifurcated extensions 39 of a controlling lever 40 are pivotally attached. The controlling lever 40 is pivotally mounted on a transverse supporting shaft 41 (see Figs. 2 and 3), said supporting shaft being mounted at its ends in 20 the side walls of a housing 42 encasing the motor and associated propeller actuating gears in the hull of the vessel. The controlling lever 40 is provided with the usual latch device 43 which engages a notched sector 44 on top of the housing 42, said controlling lever obviously operating through a slot provided therefor in the housing. Obviously, by manipulating the controlling lever 40 the clutch member 30 may be moved at will to 25 engage either of the gears 24 and 25, the releasable latch element 43 by its engagement with the sector 44 holding the clutch member in its gear engaging as well as neutral positions.

30 A rudder 45 is located adjacent to each end of the keel tube or tunnel member 17 rotatable about substantially vertical or slightly inclined axes in the median vertical plane coinciding with the longitudinal axis of the tube or tunnel 17. As shown, the pivotal axis of each rudder is inclined, that is to say, it is perpendicular to the inclination of the under end portions 12 of the hull of the vessel. Also, it is preferable to have the inner edge portion 46 of the rudder vertical or substantially parallel with the adjacent end of the tube or tunnel 17 and the bottom edge portion 47 at right angles thereto, but the outer edge portion 48 is preferably inclined 35 corresponding to the inclination of the pivotal axis of the rudder. The rudder is mounted on a shaft 49 which is supported in a suitable bearing 50 on the inclined bottom portion 12 of the hull, said shaft having a gear 51 fixed thereon which engages a pinion 52

on a steering shaft 53 having a hand wheel 54 at the upper end thereof, by which arrangements the rudder is actuated according to the manipulation of the hand wheel 54.

In steering the vessel the forward rudder 45, according to the direction of travel, is utilized, while the opposite rudder is locked in straight alignment with the longitudinal axis of the keel tube or tunnel portion 17. As a convenient means of releasably locking the rudder in this relation, the upper end of the shaft 49 is provided with a disc or head 55 (more clearly shown in Figs. 6 and 7) having a peripheral notch 56 in which a dog or latch element 57 engages, said element 57 being pivotally mounted, as at 58, on a housing 59 encasing the gears 51 and 52. In this connection, it may be here noted that, preferably, the inclined under end portions 12 of the hull are concaved, as at 60, the concavity being deepest adjacent to the ends of the keel tube or tunnel portion 17, and there corresponding to the curvature of the tube or tunnel, and gradually diminishing and disappearing towards the ends 15 where the deck portions 13 meet said inclined under portions 12. In conformity with the transverse curvature of the adjacent portion of the concavity 60 the top edge of the rudder is preferably rounded, as at 61.

By the provision of the keel tube or tunnel portion 17 with the propeller wheel 18 located therein, high propulsive efficiency is attained with a minimum expenditure of operating energy, in that a column of water is drawn into the tube or tunnel and ejected rearwardly with great force and effect, and by operating the steering rudder forward of the tube or tunnel 17 the veering or turning of the vessel is accomplished with increased facility over the ordinary methods of steering, in that the inner edge portion 46 of the propeller deflects the water from the side of the tube or tunnel to which it is turned, while the angular set of the rudder is such that the water drawn into the tube or tunnel is taken from the outside in the direction in which the vessel is turned, and at the same time the rear rudder is set in straight alignment so as not to interfere with the discharge of the column of water from that end of the tube or tunnel.

By the adaptation of the present invention in boat constructions, high speed is readily attained not only in small pleasure boats or boats for exhibition purposes, but the same advantages are attainable by the application of the invention to larger vessels of unlimited proportions, including oceangoing craft. In addition to the propulsive utility of the tube or tunnel portion 17, it stabilizes the vessel when afloat, as it obviates the necessity for providing the usual keel. The smooth riding qualities of the vessel are further enhanced by the peculiar construction and formation of the end portions of the hull, as the con-

caved under end portions 60 at the head end, in addition to directing the water in the immediate vicinity into the tube or tunnel 17, has the effect of overcoming the transverse rolling tendency of the vessel, while the same portion at the rear of the tube or tunnel 17 facilitates the propulsive effectiveness of the column of water that is discharged from the tube or tunnel. The knife-like edge portion 15 of the hull is also of material advantage when the vessel is traveling in a heavy sea, as said portion will cut through the billows so that the vessel will ride more steadily and on an even keel.

Obviously, all gearing and working parts that would otherwise be exposed to direct contact with the water, may be suitably encased in specially provided protective housings and packing glands also provided for the bearings of such shafting that enters the water. The structure may be modified in many other respects in the application and adaptation of the invention without in the least departing from the spirit and scope thereof as defined in the appended claims. The invention, therefore, is not limited to the specific construction and arrangement shown.

Having thus described my invention, what I claim as new and desire to secure by Letters Patent is:

1. In a watercraft, a hull having a submerged medial longitudinally extending open-ended tube, a propeller within said tube reversely operative and of the same effect in drawing water into the tube at either end and discharging it in a column from the opposite end, and independently operative and controllable rudders at opposite ends of said tube, the under end portions of said hull being inclined upwardly from said tube and concaved transversely of a median axis coincident with the axis of said tube.

2. In a watercraft, a hull having an open-ended tubular keel portion, means within the tubular keel portion for drawing water in at one end and discharging it from the opposite end in either direction, at will, the under end portion of said hull being inclined upwardly from the region of the adjacent end portion of the tubular keel portion and concaved transversely of a median longitudinal axis coincident with the axis of said tubular keel portion, rudders at opposite ends of said tubular keel portion, and means for independently operating said rudders to steer the craft.

3. In a watercraft, a hull having air chambered side and bottom portions and a medial longitudinally extending open-ended tubular keel portion, power actuated means for drawing water in at one end of the tubular keel portion and discharging it forcibly at the opposite end thereof from either direction, at will, the opposite under end portions of said hull being inclined upwardly, the extreme

ends converging with the ends of downwardly extending deck portions and thereby forming a transverse horizontal sharp prow edge.

4. In a watercraft, a hull having air chambered side and bottom portions and a medial longitudinally extending open-ended tubular keel portion, power actuated means for drawing water in at one end of the tubular keel portion and discharging it forcibly at the opposite end thereof from either direction, at will, the opposite under end portions of said hull being inclined upwardly, the extreme ends converging with the ends of the downwardly extending deck portions and thereby forming a transverse horizontal sharp prow edge, said deck portions being hingedly connected to said upwardly inclined under end portions whereby to be utilized as a landing bridge.

5. A watercraft comprising a hull having an upwardly inclined under end portion and a downwardly inclined deck portion merging convergently, their extreme meeting ends forming a transverse horizontal sharp prow edge, said under end portion and deck portion being hingedly connected at the prow edge whereby the deck portion may be utilized as a landing bridge.

6. A watercraft comprising a hull having air chambered side and bottom portions, and a medial longitudinally extending open-ended tubular keel portion; said keel portion extending partly into the bottom portion of the hull, but the major portion thereof projecting below the bottom of the hull to constitute the keel proper, and power means for drawing water in at one end of the tubular keel portion and discharging the water forcibly at the opposite end thereof.

In testimony whereof I have signed my name to this specification.

GUSTAF ALEXANDER.
